(57) **CLAIM**

The ornamental design for a hollow rectangular urban terrorism traffic barricade, as shown and described.

DESCRIPTION

FIG. 1 is a perspective view of a hollow rectangular urban terrorism traffic barricade showing our new design, including a molded plastic body with two recesses in the bottom side to accommodate the forks of a fork lift truck, an inlet disposed on the top side for filling the hollow rectangular urban terrorism traffic barricade 4×8 with water, an outlet on the lower-left front side to drain water from the hollow rectangular urban terrorism traffic barricade 4×8, and two recessed areas in the top side to accommodate plants or other decoration;

FIG. 2 is a front view thereof;

FIG. 3 is a rear view thereof;

FIG. 4 is a top view thereof;

FIG. 5 is a bottom view thereof; and

FIG. 6 is a side view thereof; and,

FIG. 7 is an opposite side elevational view thereof.
